UNITED STATES PATENT OFFICE.

HENRY T. NICHOLS AND CLEMENT R. FREEDE, OF SPOKANE, WASHINGTON.

CLEANING AND POLISHING COMPOSITION.

1,362,260.

Specification of Letters Patent.

Patented Dec. 14, 1920.

No Drawing.

Application filed July 23, 1919. Serial No. 312,825.

To all whom it may concern:

Be it known that we, HENRY T. NICHOLS and CLEMENT R. FREEDE, citizens of the United States, residing at Spokane, in the 5 county of Spokane and State of Washington, have invented new and useful Improvements in Cleaning and Polishing Compositions, of which the following is a specification.

10 This invention relates to improvements in polishes.

It is one of the objects of this invention to provide a polish which will serve to clean a surface as well as to impart a polishing 15 luster thereto, and in this connection, it is a feature of this invention to incorporate in the composition of our improved polish, a cleaning agent of a character that will substantially completely evaporate after it is 20 applied to such surface. An important feature of our invention, in the combination claimed, resides in employing a cleaning agent which functions in the dual capacity as such and also as a solvent.

25 A further feature of the invention consists in providing a polish composed of ingredients having the same basic properties, the one acting as a polish and the other as the solvent and cleaning agent. In this connection, it is a feature of our invention to use ingredients having such an active affinity to combine that the polish will be ready 30 for use almost immediately after it is prepared and will not have to be stored to allow the same to settle in order to form a finished mixture.

35 Specifically speaking, our composition consists of the following ingredients, combined in the proportions stated, viz: $\frac{1}{3}$ part refined crude oil, $\frac{2}{3}$ part gasoline.

The refined crude oil employed has the general consistency and character of crude oil but is much lighter in color, being white or straw color. Oil of this character is 45 known by the trade designation "Collar fuel 14+."

These ingredients are simply mixed, and in these preferred proportions, the action of the gasoline serves to thin the oil so that 50 when the polish is applied to a surface the oil will not gum the surface but will cover the same with a film which is imperceptible except for the polishing luster imparted thereto. As the polish is applied to the sur-

face, the gasoline forms a most active and 55 effective cleaning agent so that after the surface is polished it is absolutely free from dirt and grit. The gasoline thereupon begins to evaporate leaving the oil in a thin 60 film on the surface. A lighter oil than that used would not have the initial properties, after being thinned by the gasoline, of providing sufficient body to form a durable 65 polishing film on a surface and while we use a relatively heavy oil, we thin it with a solvent of gasoline sufficiently to prevent the oil from gumming but not sufficiently to impair those properties of the oil which lend 70 durability and longevity to the polishing film.

It is due in great measure to the fact that the gasoline and oil have the same properties, and to some extent the same constituents, that they so readily and easily combine 75 to form a practically homogenous fluid which does not have to be shaken when used and which remains homogenous even after standing for a long period.

Successive applications of the polish appear 80 to build up a coating on the surface as the oil appears to fill the interstices, after several applications, and not being an evaporating substance, the oil appears to build up 85 a surface over the varnish which serves to impart all the appearance of newness to the article treated.

So far as we are aware, the oil does not 90 dry and harden and therefore our improved polish may be termed flexible and can readily be applied to finish metallic parts which are capable of indenture without in any way cracking or otherwise impairing the condition of the surface polish. This would not be true of such a substance as beeswax for 95 instance, and many other substances which not only harden when they dry, but which are inherently incapable of being applied in the form of a polishing film of imperceptible thickness.

We have very successfully employed our 100 polish not only on wood articles having different characters of finish, such as furniture of different quality, as one extreme, and pianos, as another extreme, and in all of 105 these utilities, including metal surfaces, the results have been highly satisfactory.

What we claim is:—

1. A polishing liquid composition for

cleaning and polishing painted and varnished surfaces consisting of gasolene and a mineral oil combined in substantially the proportions stated, the oil being thinned by the gasolene sufficiently to leave a thin polishing film on the surface, and the gasolene acting additionally as a cleaning agent.

2. A polishing liquid composed of two-thirds part gasolene and one-third part oil.

In testimony that we claim the foregoing 10 as our own, we hereby affix our signatures.

HENRY T. NICHOLS.
CLEMENT R. FREEDE.
